(57) **CLAIM**

The ornamental design for a tear-drop shaped tag for use in a wireless tracking system, as shown and described.

DESCRIPTION

FIG. 1 is a front perspective view of a tag showing my design;

FIG. 2 is a rear perspective view of the tag;

FIG. 3 is a bottom perspective view of the tear-drop shaped tag;

FIG. 4 is a top view of the tag;

FIG. 5 is a bottom view thereof, opposite the top view of FIG. 4;

FIG. 6 is a first side view thereof;

FIG. 7 is a second side view thereof, opposite that shown in FIG. 6;

FIG. 8 is another side view thereof, 90 degrees offset from that shown in FIG. 6;

FIG. 9 is another side view thereof, opposite that shown in FIG. 8;

FIG. 10 is an exemplary environmental view illustrating the tear-drop shaped tag attached to a key ring according to some embodiments of the present invention;

FIG. 11 is a front perspective view of a tag showing my design;

FIG. 12 is a rear perspective view of the tag;

FIG. 13 is a bottom perspective view of the tear-drop shaped tag;

FIG. 14 is a top view of the tag;

FIG. 15 is a bottom view thereof, opposite the top view of FIG. 14;

FIG. 16 is a first side view thereof;

FIG. 17 is a second side view thereof, opposite that shown in FIG. 16;

FIG. 18 is another side view thereof, 90 degrees offset from that shown in FIG. 16; and,

FIG. 19 is another side view thereof, opposite that shown in FIG. 18.

In the drawings, the broken lines depict environmental subject matter only and form no part of the claimed design.
